UNITED STATES PATENT OFFICE

101,470

DESIGN FOR A HAND STAMP

Louis Melind, Chicago, Ill.

Application August 17, 1935, Serial No. 58,174

Term of patent 14 years

To all whom it may concern:

Be it known that I, Louis Melind, a citizen of the United States, residing at Chicago, in the county of Cook and State of Illinois, have invented a new, original, and ornamental Design for a Hand Stamp, of which the following is a specification, reference being had to the accompanying drawing, forming a part thereof.

Figure 1 is a front elevational view of a hand stamp showing my new design; and

Figure 2 is a side elevational view of the stamp of Figure 1.

In my design the closed substantially cubiform casing having its walls free of projections except for the screw and pins shown, with the rectangular base projecting outward beyond the casing

walls and the latter free of projections connected to the base, and the cap of substantially truncated pyramidal form centrally supporting the handle and having depending flanges forming rectangular panels at the top of the casing walls, impart to the device as a whole a novel and attractive appearance. These features, combined as shown and described, constitute the dominant features of the design of the stamp.

I claim:—

The ornamental design for a hand stamp, as shown and described.

In witness whereof, I hereunto subscribe my name this 13th day of August, 1935.

LOUIS MELIND.
